UNITED STATES PATENT OFFICE.

PATRICK W. SHIELDS, OF PITTSBURGH, PENNSYLVANIA, ASSIGNOR TO MCKENNA BRASS & MANUFACTURING COMPANY, OF PITTSBURGH, PENNSYLVANIA, A CORPORATION OF PENNSYLVANIA.

CONVEYING MECHANISM.

Application filed April 30, 1927. Serial No. 187,832.

This invention relates to conveying mechanism and is particularly useful for the conveying of containers. It is herein described in connection with the feeding of bottles to 5 a bottling machine, although it has numerous other applications.

Most bottle feeding machines are open to the objection that if the bottles are crowded there is a constant tendency for the leading 10 bottle to topple over. Various means for preventing this have been attempted, and these have been generally open to the objection that they are complicated and are not always certain in their operation.

15 I provide a simple means for preventing undue crowding of bottles. I provide a path for the bottles, with means urging the bottles therealong. This may constitute a supporting conveyor arranged with side guides, 20 the bottles being placed on the conveyor and carried therealong until they are stopped by preceding bottles, at which time the conveyor simply slides under the bottle, urging it forward. I provide a stop means adapted 25 to be moved into or out of the path and means adapted to be engaged by a bottle in the train and effective for moving the stop means into the path. Preferably the above means are embodied in a lever of the first class lying 30 alongside the conveyor, the lever having an arm so shaped as to act as a stop for the bottles when it is moved into the path thereof, the other arm lying above the conveyor, but further along in the path of the bottles, and 35 adapted to be moved outwardly when the bottles becomes crowded on the conveyor. This last arm is preferably the longer.

The arrangement is of value in any bottle feeding mechanism, but is particularly useful 40 where it is desired to divide the row of bottles into two separate streams. The long arm is found in practice to be effective for urging alternate bottles to the side of the conveyor and thus effecting a separation of 45 the bottles into two separate paths. It is therefore an extremely simple mechanism which may be used for feeding, say, a two head bottle filling machine from a single line of bottles.

50 In the accompanying drawings illustrating the present preferred embodiment of my invention as applied to a two head bottle filling machine,

Figure 1 is a top plan view of a conveyor

and feeding mechanism for the bottling machine, and

Figure 2 is a vertical section taken on the line II—II of Figure 1.

In the illustrated embodiment of the invention, there is shown a conveyor made up of 55 chain links 2 and extending from a sprocket 3 to a sprocket 4. The conveyor is provided with side guides 5 and 6. The guide 6 is provided with an adjustable support 7 whereby the effective width of the conveyor may be 60 changed. It is desired to maintain the guides 5 and 6 a distance apart which is materially 65 greater than the diameter of the bottles. The diameter of a bottle is indicated in dotted lines at B.

70 As a train of bottles is fed forward, the leading bottle engages the curved end 8 of a lever arm 9. The lever is pivotally mounted, as indicated at 10 in Figure 2, so as to swing very freely.

75 Assuming for a moment that the bottles are to be fed in a straight line along the conveyor 2, and that the side guides are so placed as to permit only this movement, it will be seen that when the leading bottle engages the curved arm 8, the short arm 11 of the lever will be swung inwardly toward the path of the on-coming bottles. The parts are so proportioned, and the guide 6 is so placed, that if there is no substantial resistance to the 80 forward travel of the bottles, the lever 9 will not interrupt their travel. This is because of the fact that the space between the conveyor guides 5 and 6 is materially greater 85 than the diameter of a bottle, and, therefore, 90 the arm 8 may be swung from the position shown in Figure 1 to such an extent that the bottles are free to pass it if they lie toward the opposite side of the conveyor, and at the same time not force the arm 11 inwardly to 95 such a distance that the forward motion of the train of bottles is interrupted.

Now assume that the leading bottle is moved past the arm 8 and is then stopped. The conveyor continues to urge the bottles from left 100 to right, as viewed in the drawings, and this results in their assuming a staggered relation on the conveyor, as shown in dotted lines at the left hand side of Figure 1. This staggering of the bottles for the entire length of the 105 conveyor is due to the bottles sliding upon one another. At least one bottle will be forced against the arm 8 and will cause it to

swing outwardly to such an extent that the inclined face 12 of the arm 11 blocks the train of bottles and prevents any further forward movement. This blocking persists until the load on the arm 8 is relieved. This may be done by continued feeding of bottles in advance of the inclined face 12 to the bottle filling machine. The relatively short line of bottles between the inclined face 12 and the filling machine proper will not seriously effect the operation of the bottle feeding means. As the filling machine continues to use up bottles, the sidewise pressure on the arm 8 will be relieved. The bottles lying ahead of the inclined face 12 will be fed forward and then the pressure of the blocked line of bottles on the inclined face 12 will cause the arm 11 to move outwardly and permit the train of bottles to again move forward. This operation will be repeated automatically whenever conditions require it.

Now referring in more detail to the Figure 1, it will be noted that the guide 6 terminates alongside a casting 13 having a guiding face 14 which is substantially a continuation of the guide 6. It is provided with an offset portion 14^a so as to provide a path of increased width opposite the curved arm 8. This arrangement provides a path P₁, and a second path P₂ for bottles, both of these paths being indicated by arrows in Figure 1. The path P₁ is extended to a greater width than the conveyor, there being provided a supporting plate 15 whose upper surface is substantially flush with the supporting surface of the conveyor 2. The bottles are guided between a flange 14^b on the casting 13 and a flange 16 on a casting 17. The path P₂ is defined by a flange 16^a on the casting 17, and a flange 18 on a casting 19. The flange 18 extends to a flange 20 on a casting 21 which, with the flange 16^a, defines a second path for the bottles. The two paths lead to different filling heads (not shown).

In operation it is desired to supply bottles to both the path P₁ and the path P₂ from the conveyor 2. The conveyor is run at such speed that there is a tendency to supply more bottles than the filling machine heads can handle. As a result, the channels between the flanges 14^b and 16 and the flanges 16^a and 18 will be constantly filled with bottles, these trains of bottles moving forward intermittently when the bottles are taken by the filling heads. This crowding is so pronounced adjacent the arm 8 that the inclined face 12 is almost constantly in engagement with the train of bottles on the conveyor 2. It is found in practice that when a bottle filling head takes a bottle from the path P₁ or the path P₂, the bottles move forward, and if a bottle is to go to the path P₁ it will be taken from a spot corresponding somewhat to the spot X₁ on Figure 1. As the next bottle moves along the conveyor 2, the pressure of bottles on the

inclined face 12 will urge the bottle crosswise of the conveyor to a point corresponding somewhat to the spot X₁, thus leaving it in position to be fed along the path P₁. If a bottle is taken from the train lying in the path P₂, the remaining bottles in the path will be moved forward, thus leaving a vacant space at a point corresponding somewhat to the spot X₂ in Figure 1. It will be understood that at this time there will be a bottle at the point X₁. Because of this fact, the arm 8 will be pushed out of the way and despite the pressure on the inclined face 12, the next bottle in the train will be fed to the spot X₂. In operation, alternate bottles will be supplied to the points X₁ and X₂ with great regularity and with no tendency for the bottles to tip over. It is found that the operation is aided by the provision of a separating roller 22 supported on the casting 17 in the position shown.

I have illustrated and described a preferred embodiment of my invention, but it will be understood that it is not limited to this form alone, as it may be otherwise embodied within the scope of the following claims.

I claim:—

1. A conveying mechanism comprising a path for articles to be conveyed, means urging a train of articles therealong, stop means adapted to be moved into or out of the path and means adapted to be engaged by an article in the train and effective by such engagement for moving the stop means into the path. 95

2. A conveying mechanism comprising a path for articles, means for urging a train of articles therealong, a pivoted arm alongside the path and adapted to be moved into or out of the path so as to check or release the train of articles, and means adapted to be engaged by an article in the train and effective by such engagement for moving the pivoted arm into the path. 105

3. A conveying mechanism comprising a path for articles, means for urging a train of articles therealong, and a lever lying alongside the path and having a short arm and a long arm, the short arm being shaped to block the train of articles when it is moved into the path, and the long arm being shaped to cause movement of the short arm into the path upon undue crowding of articles on the path. 115

4. A conveying mechanism comprising a path for articles, means for urging a train of articles therealong, and a lever lying alongside the path and having a short arm and a long arm, the short arm being shaped to block the train of articles when it is moved into the path, and the long arm being shaped to cause movement of the short arm into the path upon undue crowding of articles on the path, the lever being so positioned that the long arm lies further along the path than does the short arm. 125

5. Conveyor mechanism for articles of substantially uniform size, comprising a path of greater width than the articles, means urging a train of articles along the path, stop means 5 adapted to be moved into the path so as to check the advancing train and means lying alongside the path and adapted to be actuated by crowding of the articles sidewise in the path, said means being effective for actuating 10 the stop means.

6. Conveyor mechanism for articles of substantially uniform size, comprising a conveyor or adapted to support the articles, but permitting relative slide movement between the articles 15 and the conveyor, side guides restraining sidewise movement of the articles on the conveyor, the guides being spaced a distance greater than the width of the articles, a pivoted arm lying alongside the conveyor, the arm 20 being adapted to move into or out of the path of the articles and check movement thereof, and means actuated by sidewise crowding of the articles in the train for moving the pivoted arm into engagement with the articles.

25 7. Conveyor mechanism for articles of substantially uniform size, comprising a lever pivoted alongside the conveyor, the lever having a short arm shaped to engage advancing articles so as to block their movement, the 30 lever also having a long arm adapted to be moved upon sidewise crowding of articles on the conveyor and effective upon such movement for moving the short arm into engagement with the articles.

35 8. Conveyor mechanism comprising a conveyor adapted to support articles, but of a

character permitting relative sliding movement between the conveyor and the articles, side guides defining the path of the articles on the conveyor, and a lever pivoted alongside the conveyor, the lever having a short arm and a long arm, the arms being so positioned that the short arm will be engaged first in point of time by an article moving along the conveyor, the short arm being shaped to 40 block advancing articles, the long arm being shaped to engage articles crowded sidewise on the conveyor.

9. Conveyor mechanism comprising a conveyor adapted to support articles, but of a 50 character permitting relative sliding movement between the conveyor and the articles, side guides defining the path of the articles on the conveyor, and a lever pivoted alongside the conveyor, the lever having a short 55 arm and a long arm, the arms being so positioned that the short arm will be engaged first in point of time by an article moving along the conveyor, the short arm presenting an inclined face to advancing articles effective for 60 blocking the progress of such articles, the long arm being so shaped as to cause the inclined face to swing into engagement with the articles when the long arm is engaged by articles crowded sidewise on the conveyor, the 65 inclination of the face on the short arm being such that the articles will cause the short arm to swing outwardly when pressure on the long arm is lessened.

In testimony whereof I have hereunto set 70 my hand.

PATRICK W. SHIELDS.
